UNITED STATES PATENT OFFICE.

HARRY A. DOUGLAS, OF BRONSON, MICHIGAN.

COWL LAMP.

Application filed January 27, 1921. Serial No. 440,485.

My invention relates generally to circuit continuing devices and also, more specifically, to cowl lamps which find use upon the dashboards of automobiles. The invention 5 has for its object the provision of an improved assembly of a mounting sleeve, attachable, for example, to the dashboard of an automobile, and a holding sleeve for contact carriers and which holding sleeve is housed by the mounting sleeve, in accordance with my invention.

In the preferred embodiment of my invention there is a shell separably assembled with and within the holding sleeve, this shell 15 carrying the contact carriers that are thereby assembled in circuit continuing relation. By this construction the contact carriers are both separably assembled with the holding sleeve. When the invention is embodied in 20 a cowl lamp the mounting sleeve is formed to support the cowl over the bulb of the incandescent lamp that is disposed within the front end of the structure.

I will explain my invention more fully by 25 reference to the accompanying drawing showing two embodiments thereof and in which Fig. 1 is a longitudinal sectional view of a cowl lamp constructed in accordance with the preferred embodiment of the invention; Fig. 2 is a view partially taken on line 2—2 of Fig. 1 with the cowl removed; Fig. 3 is a front view of the structure with the incandescent lamp bulb and the cowl removed, a part being broken away for lack 35 of space; Fig. 4 is a view of a portion of the structure shown partially in elevation and partially in section; Fig. 5 is a longitudinal sectional view illustrating a modification; and Fig. 6 is a front end view of the 40 structure shown in Fig. 5 with the lamp removed, a part being broken away for lack of space.

Like parts are indicated by similar characters of reference throughout the different 45 figures.

In both forms of the invention the mounting sleeve 1 is provided with any suitable formation whereby it may be secured in place upon some form of support such as 50 the dashboard of an automobile. As illustrated, the mounting sleeve is provided with lateral projections 2 formed with screw openings 3, through which openings screws may be passed into the dashboard. A holding sleeve 4 is provided that is formed at its 55 front end with two flanges 5, 6 defining an

annular groove that surrounds the holding sleeve, the mounting sleeve having an annular wall 7, at its front end, which is received and held tightly between said flanges. The 60 holding sleeve 4 is housed by the mounting sleeve, the holding sleeve projecting rearwardly from its front end, at which end it is assembled with the mounting sleeve. The incandescent lamp 32 has its base surrounded by the front end of the holding sleeve and may be partially enclosed by a cowl 9 whose rear end is mounted to turn upon and about the front end of the mounting sleeve 1, this sleeve being reduced to form a shoulder 10 for engaging the base of the cowl. 65

The structural characteristics so far described are common to both constructions illustrated in the drawings. In the construction of Figs. 5 and 6 the base 11 of the 70 incandescent lamp is provided with bayonet projections 33 that are receivable within bayonet channels 34 formed directly in the holding sleeve 4. The contact carrier 14 is shown as being fixedly assembled with the 75 holding sleeve. The construction shown in Figs. 5 and 6 is a so-called single pole structure and in such event the contact carrier 14 carries a single current conducting element 15 with whose rear end the conducting wire 80 16 is assembled and whose forward end is assembled with a contact 17 forwardly pressed by a coiled spring 18 into connection with the contact 19 provided upon the rear face of the base of the incandescent 85 lamp bulb. 90

In the form of the invention illustrated in Figs. 1 to 4 inclusive, the contact carriers are not directly connected with the holding sleeve but are connected with a shell 20 that 95 is coupled with and within the holding sleeve 4 so that it may be withdrawn from the holding sleeve together with the rear contact carrier 21 that may be permanently coupled with the shell. As illustrated, this 100 contact carrier is provided with a spring barrel 22 that projects laterally from the carrier 21 and into the shell 20, this spring barrel serving to fixedly couple this shell and contact carrier. A spring 23 within the 105 spring barrel serves to press outwardly upon an assembling pin 24 which projects through a circular opening in the holding sleeve 4 whereby the holding sleeve and shell, together with the contact carrier 21 assembled 110 with the shell, are separably connected with the holding sleeve. By inwardly pressing 115

upon the pin 24 it may be removed from engagement with the holding sleeve to permit the shell and the contact carrier permanently assembled therewith to be withdrawn from the holding sleeve.

The structure shown in Figs. 1, 2, 3 and 4 is a so-called two pole structure, in which event the contact carrier 21 carries two contacts 25 that are forwardly pressed by coiled 10 springs 26 into engagement with the contacts 27 upon the inner face of the lamp base. These coiled springs may press rearwardly upon buttons 28 which are engageable within the grooves 29 formed upon the inner ends of 15 current conducting terminal plugs 30 that are employed to connect the contacts 25 with the source of current that is to supply the lamp. The base 31 of the lamp bulb 32 carries bayonets projections 33 that are receivable within bayonet channels 34 which are formed within 20 the shell 20 rather than within the holding sleeve 4.

While I have herein shown and particularly described the preferred embodiment of my invention I do not wish to be limited to 25 the precise details of construction shown as changes may readily be made without departing from the spirit of my invention, but having thus described my invention I claim as new and desire to secure by Letters Pat- 30 ent the following:—

The combination with a mounting sleeve having an annular wall at one end; of a holding sleeve housed by said mounting sleeve and having two flanges by and between which said annular end wall of the mounting sleeve is held; and a shell separably coupled with and within the holding sleeve. 35

In witness whereof, I hereunto subscribe 40 my name this 12th day of November A. D., 1920.

HARRY A. DOUGLAS.
